J. B. HOGE ET AL

RADIOPHONE AND TELEPHONE METERING SYSTEM

Filed Aug. 22, 1922

UNITED STATES PATENT OFFICE.

JAMES B. HOGE, OF CLEVELAND, OHIO, AND EDWARD E. CLEMENT, OF WASHINGTON, DISTRICT OF COLUMBIA, ASSIGNEES, BY DIRECT AND MESNE ASSIGNMENTS, TO EDWARD F. COLLADAY, OF WASHINGTON, DISTRICT OF COLUMBIA.

RADIOPHONE AND TELEPHONE METERING SYSTEM.

Application filed August 22, 1922. Serial No. 582,560.

To all whom it may concern:

Be it known that we, JAMES B. HOGE and EDWARD E. CLEMENT, citizens of the United States, residing, respectively, at Cleveland, in the county of Cuyahoga, State of Ohio, and Washington, in the District of Columbia, have invented certain new and useful Improvements in Radiophone and Telephone Metering Systems, of which the following is a specification, reference being had therein to the accompanying drawing.

This invention relates to combined radiophone and telephone systems in which the radiophone service and the telephone service are both to be metered. It has for its object to reduce the number of meters required, and this object is attained by connecting the metering circuits of the radiophone central switchboard to the regular telephone line meters, and operating the same when the subscribers' radiophones are in use, at periodic intervals so adjusted as to make the charges for radio service properly proportionate, all things considered, to the charges for telephone service.

We shall describe herein a type of combined system in which the radiophone subscribers' stations are located at telephone substations and are served and controlled over the same wire circuits. On the telephone side, the meters are operated by keys in the telephone operators' cord circuits, or by equivalent means such as relays in automatic switching apparatus, usually when a called subscriber answers, the charges for service being thus based on the number of effective telephonic connections. On the radiophone side the system of metering, to which we lay no claim herein as such, is based on the time-use principle, the meters being automatically actuated by relays acting periodically as long as their respective stations are in use. Charges for radiophone service are thus proportionate to the time of use as measured by recurring unit registrations. By our present invention, all units of service are registered on the same meters, and all charges for service are unified.

The invention is illustrated in the accompanying drawing, in which:

The figure is a diagram of a combined wire and radio system equipped with one set

of individual station meters at the central office.

Referring to the drawing, A is a subscriber's station equipped with telephone instruments for talking and signaling over the line wires 18-19. A' is the radiophone substation of the same subscriber, containing a radio receiver, batteries A₁ and B₁, an extension telephone set T'-t', controlled by a switch h', and a switch hook H² controlling the filament circuit and also placing a ground on the tip conductor 18 of the line when the radio receiver is in use. The extensions of line wires 18-19 to the radiophone are controlled by a cut off relay L⁴ and shunting condenser g⁴, said relay being energized by line current when the line is in use telephonically. Extension wire 19^c is connected to the bus wire 70 of the battery A₁, and extension wire 18^c goes to the switch hook H² by which it is grounded when the radiophone is in use. Branch wires 18^e and 19^e pass from the relay L⁴ as direct continuations of line wires to the telephone set T'-t'. Wire 18^e goes to the induction coil I' and by wire 75 to the switch h'. Wire 19^e goes to the transmitter T' and thence by wire 77 to the switch h'. A branch of wire 19^e goes through a condenser to the secondary of the induction coil, thence to the receiver t' and by wire 76 to the switch h'. The instruments T'-t' may conveniently be mounted on a connecting handle containing the switch h', and the transmitter end of this assembly may then be provided with an eye so that it may be hung up on the hook H², substantially as shown in Letters Patent No. 1,382,278, granted to William W. Dean, June 21, 1921.

At the central office the line wires 18-19 terminate on multiple jacks J' with which cooperate plugs typified by P', for telephonic connections. Multiple wires 18^a, 19^a and 19^b are carried to the radio switchboard where they terminate on jack J^b, the wire 19^b being continued through a back contact of cut off relay L⁶ to the bus bar of the main battery B', while the tip wire is continued through a normally open contact of the relay L⁶ to the winding of a meter test relay M', the other side of which is connected to the bus bar of the battery B'. The metering com-

mutator M^2 closes a circuit from winding of relay L^{60} to the bus bar of the battery B' periodically, at intervals determined according to the nature of the service and the charge to be made therefor. For example, if a charge of five cents is to be made for every fifteen minutes of use of the radio receivers at the substations, then the meter commutator M^2 will make one rotation every thirty minutes, and twice during every such period the relay L^{60} will be energized, and relay M' will be supplied with battery current whereby if there is a ground on wire 70 at the radiophone substation, said relay M' will pull up and register one unit of time or one unit charge on the line meter. It will be understood of course that the relays M' and L^6 and L^{60} in this case are individual to the line and to the substation, but that the meter commutator M^2 , the battery B' and the high voltage generator M^3 for supplying meter current, may all be common to the entire exchange. The relay L^{60} is responsive to the commutator M^2 only when cut off relay L^6 is deenergized, and its action is momentary, disabling the cut off relay L^6 but energizing the cut off relay L^3 on the telephone switchboard so as to leave the tip side of line clear. If a plug is in any jack, however, relay L^6 is energized thereby as well as relay L^3 , and relay L^{60} is disabled, so that when a line is connected the meter will not register. This is necessary in order to avoid false grounds through the cord circuits. The meter M shown is the regular telephone central office line meter having one high winding and one low winding, the high winding being first energized from the generator M^3 when the relay M' pulls up or the operator's key K is depressed, the construction of the meter being such that when its armature is closed against the contact point shown, the high winding will be shunted by the low winding, whereby sufficient power to turn the meter ratchet is assured.

It is to be understood that we make no claim herein to the circuit shown and described for operating the meter, or for transmitting and receiving broadcast matter. The gist of the invention in this case is simply and solely the use of the ordinary telephone

line meter at the central station to record the use of a radiophone receiver at a subscriber's station.

The operation of this system is as follows: Assuming the subscriber's radiophone A' to be in use, with a ground on the wire 18^c, this will partially complete a circuit for the relay M' which however remains open at the front contact of relay L^{60} , which is energized periodically by the commutator M^2 , its circuit extending from the main battery B' to the commutator M^2 , and through a back contact of the cut-off relay L^6 to the winding of relay L^{60} and to ground. At intervals the relay L^{60} will therefore close an operative circuit for the relay M' , as long as the ground remains on the wire 18^c at the subscriber's station; and the relay M' in pulling up connects the meter generator M^3 to the wire 19^b, and thence to the high winding of the telephone meter M , which is usually connected to the cut-off relay circuit 19^b. This generator current is of high enough voltage to energize the meter initially, and as soon as the armature is attracted sufficiently to close the short circuit through the low winding, current from the main battery will finish the meter movement, flowing through circuit 19^b, front contact of relay L^{60} from the battery B' . The operating means and circuits disclosed herein are shown and described only for the sake of convenience, and any suitable operating means and circuits may be substituted therefor.

We claim:

In a combined radiophone and telephone system, a central station having radio control apparatus and a telephone switchboard, and subscribers' stations having radio receiving sets and telephone instruments independently operable, with line wires connecting said subscribers' stations with the central station, and individual line meters at the central station, with means to register telephone use and means to register radiophone use in aggregated service units on the same meter.

In testimony whereof we hereunto affix our signatures.

JAMES B. HOGE.
EDWARD E. CLEMENT.
